UNITED STATES PATENT OFFICE

116,549

DESIGN FOR A CONTAINER FOR BOTTLED PERFUME AND THE LIKE

Percy M. Brown, New York, N. Y.

Application March 7, 1939, Serial No. 83,397

Term of patent 14 years

To all whom it may concern:

Be it known that I, Percy M. Brown, a citizen of the United States, residing at New York city, in the county of Kings and State of New York, have invented a new, original, and ornamental Design for a Container for Bottled Perfume and the like, of which the following is a specification, reference being had to the accompanying drawing, forming a part thereof.

Fig. 1 is a perspective view of a container for bottled perfume in open position, showing my new design; and

Fig. 2 is a side elevational view thereof in closed position.

The characteristic features of the design reside

in the container of the specific configuration shown, the body of which comprises a horizontally disposed receptacle having a rounded end and a superposed hinged cover formed with a tufted top surface, the depth of the receptacle being approximately twice that of the cover and the length of the body being substantially two and one-half times that of the height of the body from the base of its legs to the top surface of the cover.

I claim:

The ornamental design for a container for bottled perfume and the like, substantially as shown and described.

PERCY M. BROWN.
